GILBERT W. GOODRIDGE, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ELECTRICAL CONTACT.

965,103.

Specification of Letters Patent. Patented July 19, 1910.

Application filed May 11, 1910. Serial No. 560,640.

To all whom it may concern:

Be it known that I, GILBERT W. GOODRIDGE, a citizen of the United States of America, and residing at Bridgeport, in the county of Fairfield and State of Connecticut, have invented a certain new and Improved Electrical Contact, of which the following is a specification.

My invention relates to electrical contact devices and particularly to center contacts for plug receptacles and the like, the object of my invention being to provide an efficient spring contact the parts of which are readily assembled, the contact being at the same time readily attached securely to its carrier.

In the accompanying drawings, Figure 1 is a vertical section of a plug receptacle in which my improved center contact is employed; Fig. 2 is a similar section of portion 20 of the same on a larger scale and with the plug removed; Fig. 3 is a cross section on the line 3—3, Fig. 1, with the plug removed; and Fig. 4 is a perspective of the parts of the contact detached and before assembly.

25 The plug receptacle illustrated comprises the customary top and bottom insulating buttons A and B respectively, connected by the screw shell C from which the current is led to the shell contact of the swiveling plug 30 D through the spring fingers E.

35 My invention is embodied in the center contact of the receptacle through which the current is led to the center contact of the plug. As shown, this center contact comprises two cup shaped members 10 and 11 of different diameters, the smaller inverted and sliding as a plunger within the larger. A spring 12, confined between the bottoms of the cups, tends to force the latter apart and 40 thus insures a close contact between the center contact of the plug and the plunger cap 10 when the plug is inserted thus compressing the spring 12. The larger cup is spread at the bottom to form a flange 13 which engages beneath the lower face of the button B when inserted from beneath through the central perforation of the latter. The upper portion of the button is slit to form several lugs, some of the latter, viz., lugs 14

being spread outward to engage the flared 50 upper end of the perforation in the button to secure said cup 11 rigidly in position. The remaining lugs 15 are thrown in to engage the outwardly offset shoulder 16 near the open end of the plunger cup 10. 55

The construction described is obviously extremely simple and easy to manufacture while thoroughly efficient as a center contact. The base of the cup 11 being carried below the button B by reason of the flange 13, 60 constitutes a satisfactory center contact for engagement with the center contact of a lamp or wall socket into which the receptacle may be screwed, while the current is transmitted therefrom to the plunger cup 10 65 not only through the sliding engagement of the latter with the walls of the cup 11, but also through the spring 12 and the contact of the latter with both cups is especially close when most needed, viz., when compressed by the insertion of the plug D. 70

Various modifications of the construction shown, which do not depart from my invention will readily suggest themselves and I do not limit myself to the precise structure 75 described.

I claim as my invention:

1. A contact of the character described, comprising cupped members of different diameters, the lesser being inverted and sliding within the greater as a plunger and being offset adjacent its open end, the sides of the other member being slit adjacent its open end to form a plurality of lugs some of which are thrown in to engage the shoulder on the smaller member, in combination with a spring confined between said members and tending to force them apart, substantially as described. 80

2. A contact of the character described, comprising cupped members of different diameters, the lesser being inverted and sliding within the greater as a plunger, a spring confined between said members tending to force the same apart and engaging means to prevent the separation of said members, in combination with a support perforated to receive said contact, the larger member 85 90 95

ing shouldered at its base to engage the lower face of said support and slit adjacent its open end to form a plurality of lugs, some of which are spread to engage the up-
5 per face of said support, substantially as described.

In testimony whereof I have signed my

name to this specification, in the presence of two subscribing witnesses.

GILBERT W. GOODRIDGE.
